UNITED STATES PATENT OFFICE.

HENRY B. HIGGINS, JR., OF DENVER, COLORADO.

PUMP OR MOTOR.

Application filed February 14, 1923. Serial No. 618,892.

To all whom it may concern:

Be it known that I, HENRY B. HIGGINS, Jr., a citizen of the United States, residing at Denver, in the county of Denver and State of Colorado, have invented certain new and useful Improvements in Pumps or Motors, of which the following is a specification, reference being had therein to the accompanying drawing.

10 My invention relates to that class of pumps or motors embodying a rotor or drum fixed to an operating shaft, said rotor or drum being provided with a plurality of cylinders, and plungers operating in said cylinders, and means, such as a face cam, tilting box or tiltable swash plate, which latter term I shall hereinafter employ, adapted to be contacted by the plungers, whereby, in a pump, rotation of said shaft 15 will cause a pumping action on fluid led to the cylinders, and whereby, when the apparatus is used as a motor, rotation of said rotor or drum by compressed fluid will result in a rotation of said shaft.

20 There are several variations of this general type adapted for the application of the principle herein disclosed; for example, a pump or motor wherein the swash plate rotates and the cylinders remain stationary.

25 In hitherto known devices, as above referred to, it has been customary to regulate the stroke of the pump or motor, by tilting the swash plate with respect to the shaft, or, in other words, by varying the angle 30 of inclination of said swash plate with respect to the axis of rotation of said shaft, obviously increasing or decreasing the stroke of the plungers. Means have heretofore been provided for manually adjusting said 35 swash plate to such positions.

In all such devices heretofore referred to, a certain static pressure has always been built up on the discharge side of the pump, and on the intake side of the motor, and such pressure remains until the adjusting device is manually operated to vary the stroke of the pump or motor, until the static pressure is relieved to the desired degree.

40 One of the objects of my invention therefore is the provision of means for automatically varying the angle of inclination of the swash plate, with respect to the axis of

rotation of the operating shaft, in proportion to the degree of, and by the static pressure attained on the discharge end of a 55 pump, or the intake end of a motor. By means of such construction, I am enabled to automatically shorten the operative stroke of a pump or lengthen the stroke of a motor as the static pressure rises, and the converse 60 of each as the pressure drops.

Another object is the provision of a pump or motor so constructed as to permit of the effective operation of the aforesaid automatic regulation. 65

Other objects of my invention will become apparent from the disclosure in the following specifications and the drawings forming a part thereof.

In said drawings:

70 Figure 1 shows a partial longitudinal section taken through the pump forming the subject matter of my invention;

Fig. 2 is a section taken on line 2—2 of Fig. 1; 75

Fig. 3 is a section taken on line 3—3 of Fig. 1;

Fig. 4 is a section taken on line 4—4 of Fig. 1.

Fig. 5 shows a longitudinal section showing the swash plate in another position. 80

Fig. 6 is an end elevation of the pump;

Fig. 7 is a detail of the pivotal mounting of the swash plate.

Fig. 8 is a view similar to Fig. 5, showing a somewhat different automatic regulator; 85

Fig. 9 is a view similar to Fig. 6;

Fig. 10 is a detail section showing the attachment of the automatic regulator to 90 the swash plate;

Fig. 11 is a view of a motor equipped with my invention;

Fig. 12 is a section taken on line 12—12 of Fig. 11. 95

Now referring specifically to Fig. 1 of the drawing, A is a casing, into which projects an operating shaft B, upon which is mounted a rotor C, so connected to the shaft as to rotate therewith. Pivotaly mounted within the casing A is a swash plate D, the particular method of mounting said plate D, to be more specifically hereinafter explained. 100

The rotor C is provided with a plurality of cylinders 1, open at each end, and extending in a plane parallel to that of the shaft B. Each cylinder is provided with a 5 plunger 2, controlled by a coiled spring 3, held in position by a spring washer 4. The plungers 2 are here shown as a hollow cylindrical shell, having an open rear end, and provided with a closed outer end having a 10 rounded outer face 5, for contact with the swash plate D.

The intake end of the rotor C, is covered by a plate 6, carrying two segmentally configured ports 7, 7', best shown in dotted lines, Fig. 6. Communicating with said ports are inlet and outlet pipes 8, 8' respectively, as clearly shown.

From the foregoing it will be sufficiently understood by those skilled in the art that, 20 in operating such a pump as described, the swash plate D is normally tilted to such angle as desired, to govern the stroke of the plungers in the cylinders.

The springs 3 always press each plunger 25 outwardly so that its curved face 5 is in sliding engagement with the face of the swash plate. Rotation of the shaft B will cause the rotor C to turn, and of course cause the projecting ends 5 of each plunger 30 to ride around the face of the contacting swash plate.

In the position shown in Fig. 1, it will be noted that the swash plate D is inclined 35 inwardly at the top. The cylinders which are aligned with part 7 are taking in, from the pipe 8, the fluid being pumped, the pressure, if any, of the incoming liquid, and the pressure of the springs 3, always forcing the plungers outwardly so that the face 5 contacts the swash plate. As the plungers rise 40 they are pushed inwardly to the position shown above the shaft in Fig. 1, and the fluid in the cylinders is ejected through the port 7' to the outlet pipe 8', for delivery to 45 the desired point.

In all devices hitherto known to me, the pivoted swash plate is manually adjusted and rigidly fixed at such inclination as to properly determine the desired stroke of the 50 pump. But it is obvious that, in case where work is being performed by the fluid being ejected through the pipe 8', a static pressure is in proportion to the work performed, is developed in said pipe, between the pump 55 and the work. In the hitherto known devices, it has been necessary to relieve such pressure, when excessive, by some sort of relief valve, which is wasteful, or by manually moving said swash plate to a position more 60 nearly perpendicular to the operating shaft, thereby shortening the stroke of the pump until the static pressure has been sufficiently relieved, and to thereafter restore the swash plate to its original position, when conditions 65 are once more normal.

As herein before stated, my invention comprehends the automatic movement of the swash plate, by means of the static pressure, to automatically regulate the stroke of the pump.

The instrumentalities for effecting the automatic regulation may be described as follows:

The swash plate D comprises a cylindrical cup containing two bearing rings 9 and 10, 75 separated by anti-friction balls 11. The outer surface of the ring 10 is adapted for contact by the ends 5 of the pistons 2, and, under the friction developed by the thrust of said ends 5, is caused to run on the 80 balls 11.

As shown in Figs. 1 and 2, the swash plate D is provided on opposite sides with projecting trunnions 12, 12, and 12', 12', mounted in blocks 13, 13, 13', 13', containing 85 suitable curved sockets adapted for the reception of said trunnions. It will be noted that this construction permits the swash plate to be pivoted either on the trunnions 12, 12, or 12', 12', also that the trunnions 12, 12 are above the central line of the shaft B, and that the trunnions 12', 12' are below said central line, such arrangement constituting a feature of my automatic regulator. The upper portion of the swash plate 95 D is provided with a neck 14 adapted for attachment to the other elements of my automatic regulator.

In the upper portion of the casing A is provided a cylinder 15, in which is reciprocably mounted a barrel 16, carrying at its end nearest the swash plate, a slipper 17, pivotally secured to the neck 14 of the swash plate by means of a pin 18. The other end of the barrel 16 is closed by a perforated cap 19, through which extends a screw-threaded shaft 20, passing through a screw-threaded projection 20' carried by the casing, said shaft carrying an operating handle 21 on its outer end. On the inner end the shaft 20 carries a plunger 22, slideable within the barrel 16. Between the plunger 22 and the closed end of the barrel 16 nearest swash plate D, is loosely mounted a coiled spring 23, and another coiled spring 24 is loosely mounted between the plunger 22 and the cap 19.

It is clear that rotation of the shaft 20 in one direction will move the plunger 22 to the left to compress the spring 23, and movement in the opposite direction will compress the spring 24.

In Fig. 1 the spring 24 is greatly compressed, but plunger 22 cannot move except by rotation of the shaft 20, and the pressure of the spring 24 operates to resiliently retain the barrel 16, and swash plate D, in the position shown. It will be understood that spring 23 at this time is neutral.

The movement of the shaft 20 which pulled swash plate D away from the perpendicular, to the position shown in Fig. 1, also caused the trunnions 12, 12 to leave their sockets 13, 13, and, consequently, it will be noted that the swash plate is now pivoted below the axis of rotation of the shaft B, on the trunnions 12', 12'.

In the position as above described, as long as no appreciable resistance is met in the circulation of the fluid, it will exert no appreciable pressure upon the plungers, nor they in turn upon the face of swash plate D, and the only power required to rotate the driving shaft B is that necessary to overcome the friction of the device.

However, as soon as resistance is interposed in the path of the fluid, a corresponding static pressure is built up in the same, which pressure is immediately transferred back to the plungers and the face of swash plate D, and thence to the trunnions 12', 12'. It will be obvious that, since the center of support of swash plate D is below the center of thrust delivered by the plungers against said plate, the plungers above the shaft present the same pressure against the plate as do the plungers below, but through a longer lever arm, depending upon how far the trunnions 12', 12' are located below the axis of the rotor C. Also that there will be more plungers exerting pressure above than below the trunnions. Thus the total pressure against the face of the swash plate above the trunnions is greater than the pressure below said trunnions, resulting in a tendency to return the swash plate to a plane perpendicular to the plane of rotation of the rotor C.

The excess of static pressure above referred to acts against the pressure of the spring 24, and causes the swash plate D to more nearly approach the perpendicular, thereby additionally compressing the spring 24. Obviously such movement of the swash plate shortens the stroke of the pump, reducing the output thereof, and thereby relieves the static pressure at the outlet end, or enables the pump to operate at reduced capacity against a higher load. As the static pressure reduces, the spring 24 automatically operates to restore the swash plate to the position shown in Fig. 1, as will be understood.

It will be clear that, as swash plate D moves nearer to a plane perpendicular to the axis of rotation of the rotor C, the stroke of the plungers is shortened, and that said plungers will displace less fluid per revolution, and, conversely, when the static pressure on the fluid be decreased, spring 24 will operate to tilt the swash plate further away from the perpendicular, thereby increasing the fluid displacement per revolution, thereby automatically keeping ap-

proximately even, under all conditions, the load on the prime mover.

Fig. 5 illustrates the reverse positions of the parts wherein the direction of rotation of the drive shaft and of the rotor is the same as in Fig. 1, but wherein the swash plate has been tilted in a reverse direction, to compress the spring 23. Such movement of the swash plate has caused the pivotal points to be placed upon the trunnions 12, 12, and has caused the plungers which are aligned with part 7' to become the intake plungers, and those which are aligned with part 7 to operate as ejection plungers. It will also be clear that, for the same reasons as above set forth, static pressure now operates to additionally compress the spring 23, tending to restore the swash plate to the perpendicular as such pressure increases, and the spring 23 immediately tends to restore the swash plate to the position shown in Fig. 5, when said pressure is reduced.

Fig. 11 shows a longitudinal section of a fluid operated motor fitted with my automatic regulator. It will be observed that, in general, the machine is similar to the construction heretofore described. The swash plate D however, is not provided with the double trunnion arrangement, being pivoted above the line of rotation of the rotor C. The spring 24 has also been eliminated. In this construction fluid under pressure is introduced to the plungers above the line of rotation of the rotor C, pressing the plungers 2 forcibly against the swash plate D, and causing them to ride downwardly in clockwise direction upon the inclined face of the swash plate and thereby turn the rotor, which in turn rotates the shaft B, the latter thereby becoming a driven shaft which may be operatively connected to any desired work.

Ordinarily, when the mechanical effort required of the motor is small, there is no opportunity for any heavy static pressure to build up in the driving fluid, as the motor can rotate rapidly and thus displace enough fluid to dissipate any great pressure, and hence a slight compression of the spring 23 will hold the swash plate D in a plane nearly perpendicular to the axis of rotation of the rotor C. This results in the plungers taking a short stroke and hence displacing but a small quantity of fluid per revolution.

If the mechanical resistance to its rotation be increased, the rate of rotation of the motor will decrease, permitting an increase of static pressure in the fluid acting upon the plungers.

This increase in static pressure behind the plungers causes them to protrude further, and, since the predominating fluid pressure is below the axis of oscillation of

the swash plate D, the tendency of such pressure is to tilt the latter still further away from the perpendicular, additionally compressing the spring 23. Such movement 5 of the swash plate results in a longer stroke of the plungers 2, and hence in the displacement of more fluid, thereby increasing the mechanical power available.

When the load on the motor, and hence 10 the degree of static pressure is sufficiently reduced, the spring 23 will automatically return swash plate D toward the perpendicular thereby shortening the stroke of the plungers 2, thus displacing an amount of 15 fluid substantially in proportion to the amount of work performed, as will be readily understood.

Fig. 8 shows the same mechanism adjusted 20 for use as a pump. This adjustment is made by moving shaft 20 to the left, causing the 25 plunger to compress the spring 23 while swash plate D is so inclined that its upper portion is at the left of a plane perpendicular to the axis of rotation of the rotor C. By this construction the motor acts as a 30 pump, exactly as described in connection with the operation of the construction shown in Fig. 5.

From the foregoing it is clear that the 35 above described constructions embody means for automatically causing the static pressure to change the adjusted stroke of the pump or motor, and to automatically restore said stroke upon sufficient reduction of 40 said pressure. It will be noted that the stroke automatically varies with the rise and fall of the static pressure, which is a function of the load imposed upon the pump or motor.

The principle involved in this disclosure 45 is considered to be adaptable to wide applications which will be suggested to those skilled in the art, and the principle of operation herein described is intended to broadly cover all such modifications, adaptations or 50 embodiments as fall fairly within the scope of the appended claims.

I claim:

1. A pump or motor provided with a 55 rotating member having a plurality of cylinders carrying plungers adapted for reciprocation therein, in combination with an element mounted in position to be contacted by said plungers, said element being pivoted in a plane outside of the axis of rotation of 60 said member, substantially as described and for the purposes set forth.

2. A pump provided with a rotating member having a plurality of cylinders carrying plungers adapted for reciprocation therein, in combination with an element 65 mounted in position to be contacted by said plungers, said element being so mounted as to be capable of movement to a position 70 where it is pivoted either above or below

the axis of rotation of said member, substantially as described and for the purposes set forth.

3. A pump or motor provided with a rotating member having a plurality of cylinders carrying plungers, in combination with an element mounted for contact by said plungers and governing the working stroke thereof said element being so pivoted that the predominating force of the plungers will be exerted on said element at one side 75 of the axis of rotation of said member, and means resiliently opposing said predominating force, substantially as described.

4. A pump or motor provided with a rotating member having a plurality of cylinders carrying plungers adapted for reciprocation therein, in combination with a pivoted element adapted for contact by said plungers and governing the stroke thereof, said 85 element being so mounted that the predominating force of the plungers is applied on one side of the axis of rotation of said member, substantially as described.

5. A pump or motor provided with a rotating member having a plurality of cylinders carrying plungers adapted for reciprocation therein, in combination with a pivoted element adapted for contact by said plungers and governing the stroke thereof, said 95 element being so mounted that the predominating force of the plungers is applied on one side of the axis of rotation of said member, and resilient means bearing on said element in opposition to said predominating force, substantially as described.

6. A pump or motor provided with a rotating member having a plurality of cylinders carrying plungers adapted for reciprocation therein, in combination with a pivoted element adapted for contact by said plungers and governing the stroke thereof, said element being so mounted that the predominating force of the plungers is applied on one side of the axis of rotation of said member, and a compression spring bearing on 105 said element in opposition to said predominating force, substantially as described.

7. A pump provided with a rotating member having a plurality of cylinders carrying plungers adapted for reciprocation therein, in combination with an element adapted for contact with such plungers to govern the stroke thereof, said element being mounted for movement to a position whereby its axis of oscillation is on one side of the axis of rotation of said member, and to another position where the axis of oscillation is on the other side of the axis of rotation of said member, substantially as and for the purposes set forth.

8. A pump provided with a rotating member having a plurality of cylinders carrying plungers adapted for reciprocation therein, in combination with an element 120

adapted for contact with said plungers to govern the stroke thereof, said element being mounted for movement to a position whereby its axis of oscillation is on one side of the 5 axis of rotation of said member, and to another position where its axis of oscillation is on the other side of the axis of rotation of said member and means operating to resiliently retain said member in either of 10 its pivoted positions, substantially as and for the purposes set forth.

9. A pump or motor provided with a rotating member having a plurality of cylinders carrying plungers adapted for reciprocation therein, and with a tilttable element adapted for contact with said plungers to govern the working stroke thereof, in combination with means for tilting said element to either side of a plane perpendicular 20 to the axis of rotation of said member, and means resiliently retaining said element in such tilted position.

10. A pump or motor provided with a rotating member having a plurality of cylinders carrying plungers adapted for reciprocation therein, and with a tilttable element adapted for contact with said plungers to govern the working stroke thereof, in combination with means for tilting said element 30 to either side of a plane perpendicular to the axis of rotation of said member, and means resiliently retaining said element in such tilted position, said means comprising a coiled spring in operative connection with 35 said element.

11. A pump or motor provided with a rotating member having a plurality of cylinders carrying plungers adapted for reciprocation therein, and with a tilttable element 40 adapted for contact with said plungers to govern the working stroke thereof, in combination with means for tilting said element to either side of a plane perpendicular to the axis of rotation of said member, and means resiliently retaining said element in such tilted position, said means comprising a barrel 45 slidably mounted in a cylinder and connected to said element, and means bearing upon said barrel and resiliently retaining said element in such tilted position.

12. A pump or motor comprising a casing provided with a rotating member having a plurality of cylinders carrying plungers adapted for reciprocation therein, and with a tilttable element adapted for contact 55 with said plungers to govern the working stroke thereof, in combination with means for tilting said element comprising a barrel pivotally secured to one side of said element, and slidably in bearings in said casing, a piston mounted in said barrel, a coiled spring in said barrel subject to compression by said piston and adapted to resiliently retain 60 said element in its tilted position, and means for moving said piston to increase or 65

decrease the compression of said spring, substantially as described.

13. A pump or motor comprising a casing provided with a rotating member having a plurality of cylinders carrying plungers 70 adapted for reciprocation therein, and with a tilttable element adapted for contact with said plungers to govern the working stroke thereof, in combination with means for tilting said element comprising a barrel pivotally secured to one side of said element, and slidably in bearings in said casing, a piston mounted in said barrel, a coiled spring in said barrel subject to compression by said piston and adapted to resiliently retain said 75 element in its tilted position, and means for moving said piston to increase or decrease the compression of said spring, said means comprising a shaft projecting through and in screw-threaded engagement with said 80 casing and connected to said piston, and means for rotating said shaft.

14. A pump or motor provided with a rotating member having a plurality of cylinder carrying plungers adapted for reciprocation therein, in combination with a pivoted element adapted for contact by the plungers to govern the stroke of the latter, and means adapted to resiliently hold said element in a plane at an angle to a plane 95 perpendicular to the axis of rotation of said members.

15. A pump or motor provided with a rotating member having a plurality of cylinders carrying plungers adapted for reciprocation therein, in combination with a pivoted element adapted for contact by the plungers to govern the stroke of the latter, means for adjusting said element to a position at an angle to a plane perpendicular 100 to the axis of rotation of said member, and means adapted to resiliently retain said element in its adjusted position.

16. The combination of an unbalanced element, in a mechanism for the conversion 110 of rotary motion into linear motion, or vice versa, with a resilient force adapted to oppose the predominating force acting upon said unbalanced element, in a manner that will cause the mechanism to produce less 115 linear motion per rotation, in proportion as resistance is imposed upon the output of said linear motion, in the first instance, and the production of fewer rotations of the mechanism per unit of linear motion, in proportion to the resistance offered to said rotation, in the second instance, substantially as described.

17. In a mechanism for the conversion of 125 rotary motion into linear motion, the combination of an unbalanced element and a resilient member adapted to act upon said unbalanced element in opposition to the major pressure affecting same, the co-operation of which will automatically cause the 130

production of less linear motion per rotation, but with proportionately greater force, as resistance is imposed upon the output of said linear motion, substantially as described.

18. In a mechanism for the conversion of rotary motion into linear motion, the combination of an unbalanced element and a resilient member adapted to act upon said unbalanced element in opposition to the major pressure affecting same, the co-operation of which will automatically cause said mechanism to produce more linear motion per rotation, but with proportionately less force, as resistance is removed from the output of said linear motion, substantially as described.

19. In a mechanism for the conversion of linear motion into rotary motion, the combination of an unbalanced element and a resilient member adapted to act upon said unbalanced element in opposition to the major pressure affecting same, the co-operation of which will automatically result in the production of fewer rotations per unit of linear motion in proportion to an increase in resistance offered to said rotary motion, substantially as described.

20. In a mechanism for the conversion of linear motion into rotary motion, the combination of an unbalanced element and a resilient member adapted to act upon said unbalanced element in opposition to the major pressure affecting same, the co-operation of which will automatically result in the production of more rotations per unit of linear motion in proportion to a decrease in resistance offered to said rotary motion, substantially as described.

21. In a pump, the combination of an unbalanced driving element and a resilient member adapted to act upon said un-

balanced element in opposition to the major force affecting same, the co-operation of which will automatically cause said pump to move a lesser quantity of fluid per unit of motion imparted to it, but with proportionately greater force, as resistance is offered to the passage of said fluid, substantially as described.

22. In a pump, the combination of an unbalanced driving element and a resilient member adapted to act upon said unbalanced element in opposition to the major force affecting same, the co-operation of which will automatically cause said pump to move a greater quantity of fluid per unit of motion imparted to it, but with proportionately less force, as resistance is removed from the passage of said fluid, substantially as described.

23. In a fluid operated motor, the combination of an unbalanced element and a resilient member adapted to act upon said unbalanced element in opposition to the major force affecting same, the co-operation of which will automatically cause said motor to utilize more fluid per unit of motion produced, in proportion to the resistance offered said motion, substantially as described.

24. In a fluid operated motor, the combination of an unbalanced element and a resilient member adapted to act upon said unbalanced element in opposition to the major force affecting same, the co-operation of which will automatically cause said motor to utilize less fluid per unit of motion produced, in proportion to the removal of resistance offered said motion, substantially as described.

In testimony whereof I hereunto affix my signature.

HENRY B. HIGGINS, JR.
